UNITED STATES PATENT OFFICE.

CHARLES T. SCHOEN, OF PHILADELPHIA, PENNSYLVANIA.

CENTER-BEARING PLATE FOR CARS.

SPECIFICATION forming part of Letters Patent No. 440,335, dated November 11, 1890.

Application filed July 30, 1890. Serial No. 360,392. (No model.)

To all whom it may concern:

Be it known that I, CHARLES T. SCHOEN, a citizen of the United States, residing at Philadelphia, in the county of Philadelphia and State of Pennsylvania, have invented a certain new and useful Improvement in Center-Bearing Plates for Railway-Cars, of which the following is a full, clear, and exact description.

10 This invention relates to that class of center-bearing plates which are usually and by preference struck up in dies of plate-steel; or, in other words, the invention relates to pressed-steel center-bearing plates.

15 In the interchange of my pressed-steel center-bearing plates for the cast-iron and other center-bearing plates among the railroads of this country I have found it necessary to vary the form and construction in order to meet 20 the requirements of the companies; but without specifying at this time wherein the present invention differs from the center-bearing plates heretofore patented to me I will proceed to set forth my invention, and finally 25 particularly point out and claim the part or improvement constituting my said invention.

In the accompanying drawings, illustrating my invention, in the several figures of which like parts are similarly designated, Figure 1 30 is a plan view. Fig. 2 is a central longitudinal section, and Fig. 3 is a central transverse section.

The body-plate *a* is made with a central cup *b*, which in turn is provided with a central reversely-turned frusto-conical tubular flange *c*. The truck-plate *d* is provided with a saucer-like cavity *e*, elevated from the body of the plate and of complementary shape, and to receive the cup of the body-plate, and this 35 saucer-like cavity is provided with a central upturned frusto-conical flange *f*, which fits loosely within the flange *c* of the body-plate. The plates *a* and *d* are provided with dowels *g* and *h*, respectively, for use in securing them 40 to the body and truck timbers. These plates are of pressed steel or struck up in dies by preference. I prefer to employ, in connection with these plates, cast-metal filling-pieces *i* and *j*, respectively, which filling-pieces are 45 made of skeleton form and fitted in the cavi-

ties formed by striking up the cup and saucer in the respective plates. The filling-piece *i* has the flange *k*, perforated centrally to form a bearing for the king-bolt, and is provided, also, with dowels *l* to enter the body-bolster. 55 The filling-piece *j* is provided with a centrally-perforated lug *m* to receive the king-bolt, and also to re-enforce the flange *f*. This filling-piece *j* is provided, also, with dowels *n* to enter the truck-bolster. These filling-pieces 60 serve to prevent the plates from being crushed in use by affording bearings for their cup and saucer, respectively, which bearings extend to the base-line of the plates and come in contact with the portions to which they 65 are attached. The filling-pieces may be omitted, however, and in such case the flanges *c* and *f* will be made of less diameter—that is to say, sufficient to take in the king-bolt—but, as already indicated, I prefer to employ 70 the filling-pieces.

The general outline of the skeleton filling-pieces is shown in Fig. 1, and the details of their form and construction are more fully 75 shown in the other figures.

It will be observed that the filling-pieces are made to conform to the shape of the cup and saucer, respectively. The filling-piece *i* serves to re-enforce or brace the flange *c*, just as the perforated lug of the filling-piece *j* reinforces the flange *f*. 80

The employment of the frusto-conical flanges *c* and *f* enables me to manufacture the plates more expeditiously and of greater strength than were these parts cylindrical, as 85 has been proposed, and, moreover, the fitting and movement of parts are facilitated.

What I claim is—

1. Center-bearing plates for railway-cars, composed of a body-plate and a truck-plate 90 struck up in dies from plate metal, preferably steel, of substantially uniform thickness throughout, the former having a cup-like projection constructed with a central upturned frusto-conical flange and the latter having a 95 saucer-like cavity, also provided with a central upturned frusto-conical flange fitting loosely within the flange of the body-plate, the cup and saucer being complementary one to the other, and in superficial contact, essen- 100

tially, throughout their entire area, so as to afford extended bearings one for the other, substantially as and for the purpose described.

2. Center-bearing plates for railway-cars, consisting of a body-plate struck up from plate metal and provided with a cup, and a truck-plate also struck up from plate metal and provided with a saucer complementary to the cup, combined with filling-pieces of cast metal inserted in the cup and saucer, substantially as described.

3. Center-bearing plates for railway-cars, consisting of a body-plate struck up from plate metal and provided with a cup, and a truck-plate also struck up from plate metal and provided with a saucer complementary to the cup, combined with filling-pieces of cast metal inserted in the cup and saucer and forming bearings for the king-bolt, substantially as described.

4. Center-bearings for railway-cars, consisting of a body-plate struck up from plate metal with a cup having a reversely-turned frusto-conical flange, and a truck-plate also struck up from plate metal, and having a saucer provided with an upturned frusto-conical flange, combined with a filling-piece for the body-plate, having a flange constituting a bearing to the king-bolt, and also having a portion reinforcing the flange of the cup, and a filling-piece for the truck-plate, having a perforated lug re-enforcing the flange of the saucer and also forming a bearing for the king-bolt, substantially as described.

In testimony whereof I have hereunto set my hand this 29th day of July, A. D. 1890.

CHARLES T. SCHOEN.
